PRECAST REINFORCED MASONRY WALL

Maurice Boss, Jr., and Orrie Boss,
Grand Rapids, Mich.

Application January 3, 1947, Serial No. 720,054

3 Claims. (Cl. 72—16)

1

This invention relates to improvements in a wall structure and wall construction unit.

The principal objects of this invention are:

First, to provide a building structure which enables the very rapid and economical erection of a building.

Second, to provide a building construction in which a single type of unit functions both as a vertical support and side closure in the building wall.

Third, to provide a construction unit or slab for the construction of buildings which will be both light and sufficiently strong to support the required vertical loads encountered in various types of building construction.

Fourth, to provide a building construction unit which materially reduces the amount of expensive lumber and metals required to complete the walls of a building.

Fifth, to provide a construction unit which may be erected quickly and accurately by relatively inexperienced workmen.

Sixth, to provide a construction unit which performs both the vertical load carrying functions and side closing functions of a building wall.

Seventh, to provide a building construction unit which is easily and inexpensively manufactured and easily transported due to its light weight.

Other objects and advantages pertaining to the details and economies of the invention will be apparent from the following description and claims.

The drawings, of which there are two sheets, illustrate a preferred form of our building structure and unit as applied to domestic dwellings, garages and the like, and several modified forms of units of stronger character which are adapted to larger structures than the average dwelling and garage buildings.

Fig. 1 is a front elevational view partially broken away of the wall of a building embodying my invention.

Fig. 2 is a fragmentary horizontal sectional view along the line 2—2 of Fig. 1.

Fig. 3 is a fragmentary vertical sectional view along the line 3—3 of Fig. 1.

Fig. 4 is a fragmentary vertical sectional view along the line 4—4 of Fig. 1.

Fig. 5 is a fragmentary sectional view similar to Fig. 2 but showing an exterior wall unit joined to an interior wall.

Fig. 6 is a perspective view of our wall unit.

Fig. 7 is a plan view of a modified form of wall unit adapted for heavy construction.

2

Fig. 8 is a fragmentary perspective view partially in cross section showing the construction unit illustrated in Fig. 7 in erected position.

Fig. 9 is a plan view of a further modified form of wall unit for heavy construction.

Fig. 10 is an elevational view partially in cross section of a further modified form of wall unit with provision for the installation of electric wiring therein.

10 Fig. 11 is a perspective view of a modified form of unit adapted to be cut into short sections.

Fig. 12 is a top view of another modified wall unit.

15 Fig. 1 represents the wall of a building 1 built upon a foundation or footing 2 and defining a door opening 3 and window opening 4. The wall is constructed of a series of our construction units or slabs 5 and is finished at the top with a pair of plates 6 of standard 2" x 4" timber construction. No attempt has been made to illustrate the roof construction since any desired form of construction may be built on the plates 6.

20 As is most clearly shown in Figs. 2 and 6, the slabs or construction units 5 consist of a mass of concrete which is made with a vermiculite or other light weight aggregate indicated at 7 embedded in a suitable binder such as Portland cement. The slabs 5 are formed with a tapered groove 8 along one edge longitudinally thereof and a tapered tongue 9 along the opposite edge. The tongues in the example illustrated are slightly higher than the depths of the grooves 8 so that a groove 10 is formed between the adjacent units when they are erected. The edges of the units are further beveled as at 11 thus widening the edges of the grooves. The grooves are filled after the 25 units are erected with a suitable mortar which on the inside of the building may consist of a vermiculite plaster indicated at 12.

30 Integrally formed or cast within each unit or slab 5 is a longitudinally extending stud 13 which is preferably formed of creosoted lumber and when used for dwelling construction is approximately two inches square. As is most clearly shown in Figs. 3 and 6, the studs 13 extend beyond the top and bottom ends of the units 35 as at 14 to provide means for anchoring the individual units to the footing 2 and plates 6.

35 In assembly, the lower extension 14 of the stud is seated in a preformed channel or slot 15 in the top of the footing 2 and the lower 40 plate 6 is secured to the top extension 14 by 45

means of a spike 16. A filler strip 17 of wood is positioned between the under side of the lower plate 6 and the tops of the building units 5 and serves as a nailing strip for a molding, should this be desired. The space on the outside of the wall between the lower plate 6 and the tops of the building units is filled with a mortar as at 18.

The door and window openings 3 and 4 are formed with a lintel unit 19 which is slightly different from the side units 5 in that it is formed with grooves 20 on opposite sides thereof, the upper groove being arranged to receive the lower ends of the studs 13 in the vertical units and the lower groove 20 being adapted to receive a nailing strip 21 to which a standard frame member 22 may be nailed. The lintel members 19 extend across the window and door openings and rest upon the upper ends of wall units 23 which are shorter than the standard wall units. The wall units 24 above and below the window opening and above the door opening are, of course, shorter than the full length wall units 5.

The footing 2 may be provided with a shoulder 25 around the inside thereof arranged to support standard floor joists 26 on which floor boards 27 are secured in the normal fashion. Where it is desirable to use the same wall unit in an interior wall this may be done as is shown in Fig. 5 by providing a wall unit 5A having an extra tongue 30 28A formed on the side thereof and arranged to engage the groove in the interior wall unit 5. The junction between the interior wall and the opposite exterior wall will, of course, be with a groove formed in the side of the exterior wall unit.

Figs. 7 and 8 illustrate a modified form of wall unit and construction which is adapted for buildings carrying heavier roof loads such as large commercial buildings and factories having large doors and machinery supported from the roof beams. In this form of construction the wall unit 28 is formed in the same shape as the wall unit 5 previously described, but is provided with a stud 29 formed of standard shape angle iron which is positioned off center close to the inner edge of the wall unit. As in the first form of construction just described, the studs 29 extend beyond the ends of the wall units and are adapted to be welded as at 30 to the edge of an I-beam top plate 31 on the top of the wall. The lower ends of the studs are welded as at 32 to a metal sill 33 secured to the footing 34 by bolts poured in the footing. The inner edge of the footing is beveled off as at 35 permitting access with an arc welding rod to the ends of the studs and the metal sill. A concrete floor 36 may be poured over the junction between the wall units and the footing after the weld 32 is completed.

Fig. 9 illustrates a modified form of a wall unit 28A in which the stud 29A consists of a tubular iron plate. The pipe 29A is positioned in the middle of the wall unit and does not extend beyond the ends of the unit. In this form the stud rests on the plate 33 and under the I-beam 31 to support the vertical load of the roof. A practical use of this unit is to use it alternately with the unit 28 shown in Fig. 7 to support the roof while units 28 align the wall.

Fig. 10 shows a further wall unit 5B which is in all respects the same as the preferred wall unit 5 except that a core is placed in the unit prior to pouring the concrete to form a bore 37 longitudinally therethrough. After the unit 5B is erected in a building holes may be drilled 70 75

through the inner or outer surfaces of the unit as at 38 to communicate with the bores 37 for running electric or telephone wires through the bore.

Fig. 11 shows a modified form of wall unit 5C in which one or more divider plates have been placed in the mold prior to pouring the unit and thereafter removed forming slots 39 at predetermined intervals which permit easy access to the stud, either wood as shown or metal, for sawing the unit into short lengths such as those over the windows and doors. The sectionalized unit is held together by the stud for convenient handling and transportation until it is ready to be used.

Fig. 12 illustrates a further modified form of wall unit 28B having a stud 29B formed of two light sheet metal channels 40 joined together in back-to-back relationship. The webs of the channels are slightly bent or folded as at 41 and the stud is positioned near the inner side of the wall unit so that nails may be driven between the channel members as desired for supporting pictures or moulding on the inside wall of the house.

The studs 29B extend beyond the top of the body of the wall unit and the flanges of the channel members are apertured as at 42 to receive screws for securing a light downwardly facing channel shaped plate along the tops of the wall units. The studs 29B are presently available under the commercial trade name of "Stran-Steel."

In all forms of the building unit illustrated, the stud member, either metal or wood, acts both to carry part of the vertical load of the plates on the wall and to mutually reinforce and be reinforced by the concrete of the wall unit. The studs further act for form aligning members for successive wall units so that relatively inexperienced workmen may erect the units without danger of misaligning the units or curving the wall. The units may be economically formed by pouring the vermiculite concrete in suitable molds to form a few standard shapes and are easily and cheaply transported after construction due to their light weight.

We have described our wall unit in several highly practical forms thereof for use both as exterior and interior wall units for either dwelling or commercial structures. Other modifications of the construction unit such as other shapes of stud members and oblique angle wall junction members should be readily apparent where the use of these modified forms are desirable.

Having thus described our invention, what we claim as new and desire to secure by Letters Patent, is:

1. A building construction in combination with a footing having a metal sill secured to the upper surface thereof, said building construction comprising a plurality of interlocking wall units and extending the full height of the wall, metal reinforcing stud members of angle shaped cross section positioned within the body of said wall units and closer to the inner surface thereof, said stud members extending beyond the ends of said wall units, and a plate of I-beam cross section supported upon the top of said wall units, the upper ends of said studs being welded to the inner edge of said I-beam, the lower ends of said studs being welded to the inner edge of said sill, the inner edge of said footing being beveled to permit access to the lower ends of said studs, the body of said wall units being made of concrete with a vermiculite aggregate.

2. A building construction in combination with a footing having a metal sill secured to the upper surface thereof, said building construction comprising a plurality of interlocking wall units extending the full height of the wall, and metal reenforcing stud members positioned within the body of said wall units and closer to one surface thereof, said stud members extending beyond the lower ends of said wall units, the lower ends of said studs being welded to the inner edge of said sill, the inner edge of said footing being beveled to permit access to the lower ends of said studs, the body of said wall units being made of concrete-like material with a light weight aggregate.

3. A building construction in combination with a footing having a metal sill secured to the upper surface thereof, said building construction comprising a plurality of wall units extending the full height of the wall, metal reenforcing stud members positioned within the body of said wall units and closer to one surface thereof, said stud members extending beyond the ends of said wall units, and a metal plate member supported upon the top of said wall units, the upper ends of said studs being welded to the edge of said plate, the lower ends of said studs being welded to the edge

5

of said sill, one edge of said footing being beveled to permit access to the lower ends of said studs, the body of said wall units being formed of concrete-like material with an aggregate of lighter weight than stone.
